UNITED STATES PATENT OFFICE

FRANK A. DONALDSON, OF MINNEAPOLIS, MINNESOTA

AIR CLEANER

Application filed October 16, 1924. Serial No. 743,980.

My present invention provides an extremely simple and highly efficient air cleaner especially adapted for use to deliver to the carburetors of internal combustion engines clean air, that is, air freed from dust; and, generally stated, the invention consists of the novel construction, combinations and arrangements of parts hereinafter described and defined in the claims.

10 I shall first describe several forms of the improved air cleaner and will thereafter consider the nature and the importance of various novel features therein involved.

15 In the accompanying drawings, which illustrate the invention, like characters indicate like parts throughout the several views.

Referring to the drawings:

Fig. 1 is a view showing the improved air cleaner connected to the carburetor of an internal combustion engine, the said carburetor and engine being indicated diagrammatically;

20 Fig. 2 is a transverse vertical section on the lines 2—2 of Figs. 1 and 3;

Fig. 3 is a vertical axial section on the line 3—3 of Fig. 2;

25 Fig. 4 is a rear end elevation of the air cleaner, looking into the air-receiving end thereof;

Fig. 5 is a view corresponding to Fig. 3, but illustrating a modified form of the cleaner and showing in diagram a carburetor to which it is connected;

30 Fig. 6 is an elevation looking into the air-receiving end of the cleaner shown in Fig. 5;

Fig. 7 is a transverse section on the line 7—7 of Fig. 5;

35 Fig. 8 is a transverse section on the line 8—8 of Fig. 5; and

Fig. 9 is a view chiefly in diagram but with some parts in full shaded lines, showing the manner in which an air cleaner, such as that illustrated in Fig. 5, may be connected to a carburetor and to the exhaust pipe of an internal combustion engine.

40 Figs. 1, 3, 5 and 9 illustrate diagrammatically an internal combustion engine 10, an intake manifold 11, an exhaust manifold 12, an exhaust pipe 13, and a carburetor 14, the

latter connected to the intake manifold in the usual way, and all of said parts being of the usual or any suitable construction.

Figs. 1 to 4, inclusive, illustrate a form of the air cleaner believed to be of the best 55 design for use in connection with Ford automobiles and for some other purposes, and this construction will be first described.

Preferably, the casing or body shell of this air cleaner is a thin sheet metal cylinder 15, 60 closed at one end by a head 16 and horizontally disposed, the same being supported in such position, at least in part, by one of the customary manifold clamps 17, such as found on Ford engines, the said clamp being arranged to grip and hold flanges 18 secured to and projected upward from said casing 15. At its open end, that is, at the end opposite to the head 16, the cylindrical casing 15 is provided with an inset circumferentially spaced series of spiral vanes or blades 19 that will cause the air drawn into the casing to take up a whirling motion. These vanes 19 are soldered or otherwise rigidly secured to the casing and, at the axis of the 65 casing, they are overlapped in such a way that, for a considerable area, such as approximately that represented by the dotted circle marked y on Fig. 4, air cannot pass axially on a straight line into the casing. 70

most portion of the separating chamber A into the upper portion of the dust chamber C. A clean air tube 24 is secured to the casing 15 and leads directly downward from the clean air chamber B and, as shown, is connected to the carburetor 14 by an air pipe 25. At the bottom of the dust chamber C, the casing 15 is provided with a depending cleanout passage formed in a short threaded nipple 26 that is normally closed by a co-operating threaded cap 27.

It will be noted that the dust port or passage 15 is formed by pressing an upper portion of the diaphragm 20 away from the separating chamber A and into the dust chamber C. It should be also noted that the spiral vanes 19 are turned in such a direction that the air taken into the separating chamber A will be whirled in a clockwise direction in respect to Fig. 4, which is in a counterclockwise direction in respect to Fig. 2, and it will be further noted that the pressed lip that affords the passage 22 is circumferentially beveled or spiraled in the same direction as the vanes 19, so that the dust, on striking the said lip, will pass freely into the dust-collecting chamber C.

The action of this air cleaner in the form just described, is substantially as follows:

Under the suction produced in the carburetor while the engine is in action, partial vacuum will be maintained in the clean air chamber B and, hence, in the separating chamber A, so that the dust-laden air from the exterior will be drawn into the open end of said chamber A and, by the spiral vanes 19, will be caused to take a whirling motion within the separating chamber A. This whirling motion will cause the heavier particles, such as dust, to be thrown against the cylindrical wall of the separating chamber and to take a spiral motion against the diaphragm 20, so that the dust, on reaching the dust port 22, will be thrown into the dust chamber C. In this action, gravity is not relied upon to separate the dust from the air, but, on the contrary, the separation is made somewhat against the action of gravity and by centrifugal force, which whirls or throws the dust particles outward and through the dust port 22, while the air freed therefrom, being relatively light, will pass through the air port 21 and into the clean air chamber B and from thence to the carburetor. The fact that the port 21 is in a sleeve that projects from the diaphragm 20 into the separating chamber, facilitates the separation of air from dust, for it, with the diaphragm and cylindrical wall of the chamber A, affords a sort of an annular runway in which the dust may whirl until it passes through the port 22 into the dust-receiving chamber C.

From the foregoing, many of the advantages of using a cylindrical casing and of placing the same in a horizontal position

should be apparent. The arrangement of the partition structure locates the separating chamber, clean air chamber and dust chamber all within the cylindrical casing, and the location of the dust port 22 at the top of the casing makes it possible to utilize the interior of the cylindrical casing as a dust chamber and to nearly or quite fill said dust chamber with dust before it is necessary to clean out the same.

In the modified arrangement illustrated in Figs. 5 to 8, inclusive, the casing is again preferably a horizontally disposed cylindrical casing 15^a provided at its air-receiving end with spiral vanes or blades 19^a of substantially the same arrangement as the blades 19. In this structure, the casing is divided into three chambers, to wit: a separating chamber *a*, a clean air chamber *b* and a dust-receiving chamber *c*, by a partition structure made up of an axial tube 28 and an annular partition or diaphragm 29. The air port that connects the chamber *a* to the chamber *b* is formed by the extreme inner end of the tube 28 and the outer end of said tube is directly connected to the carburetor 14. The dust-receiving port 22^a, which is like the port 22, is located in the extreme uppermost portion of the partition 29, and the dust chamber *c* is of annular form and completely surrounds the tube 28. At its bottom, said chamber *c* is provided with a cleanout port 30, which, as shown, leads to a short threaded nipple 31 secured to the bottom of the casing 15 and normally closed by a screw-threaded cap 32. Also, as shown in Figs. 5 and 6, a small cap *y'* is applied to the axial portions of the spiral vanes 19^a, to prevent flow of air into the casing 15, closely adjacent to or surrounding the axis thereof.

The operation of this modified form of the air cleaner illustrated in Figs. 5 to 8, inclusive, is substantially like that of the structure above described and illustrated in Figs. 1 to 4, inclusive, except that the air passes directly rearwardly from the clean air chamber *b* to the carburetor and that the dust in the chamber *c* will accumulate around the axial tube 28.

In Fig. 9, I have illustrated an arrangement for connecting the bottom of the dust chamber to the exhaust pipe of the engine, so that, by the action of suction, the dust will be drawn from such chamber; and in this illustration, I have shown the air cleaner illustrated in Figs. 5 to 8 with a dust discharge pipe 33 attached to the cap 32 and opening therethrough and having its discharge end extended into the engine exhaust pipe 13 in such a manner that the force of the exhaust will produce partial vacuum in the said tube 33 and, hence, in the dust chamber. With such an arrangement, as is evident, dust will not accumulate in the dust

chamber *c* but will be continuously drawn therefrom.

What I claim is:

1. An air cleaner comprising a tubular casing formed with a separating chamber through which the air moves without reversing its direction of travel, said separating chamber at one end having means for causing the incoming air to take a whirling motion and provided at its other end with an axial air discharge port of less cross section than said separating chamber, and a dust chamber having a port located in the upper portion of said chamber and eccentric to said air outlet port and connecting said separating chamber to said dust chamber. 70
2. The structure defined in claim 1 in which said air outlet port is formed by a sleeve that projects into said separating chamber beyond said dust port. 80
3. An air cleaner comprising a tubular casing set on an approximately horizontal axis and provided at its air intake end with a device causing the incoming air to take up a whirling motion within said casing, an annular partition applied in said casing and spaced axially back from the air intake end of said casing and having a centrally located air outlet port, said annular partition at its upper portion having a dust port, a supplemental partition connected to said annular partition at a point below said dust port and above said air outlet port and dividing the rear portion of said casing into a clean air chamber and a dust chamber into which latter said dust port opens, said clean air chamber having an outlet adapted to be connected to a carburetor. 85
4. The structure defined in claim 3 in which said annular partition is provided with a sleeve surrounding the air outlet port thereof and projecting toward the air intake end of said casing. 90
5. The structure defined in claim 3 in which said annular partition is provided with a sleeve surrounding the air outlet port thereof and projecting toward the air intake end of said casing, the said dust chamber having a depending cleanout nipple and a detachable cap normally closing the same. 95
6. An air cleaner comprising a casing provided with a partition structure dividing the same into three chambers, to wit: a separating chamber, a clean air chamber and a dust chamber, said separating chamber having an air inlet opening thereinto from the atmosphere, and provided with a device causing the incoming air to take a whirling motion within said separating chamber, said partition structure having a centrally located air port and an eccentrically located dust port, said air port connecting said separating chamber to said clean air chamber and said dust port connecting said separating chamber to said dust chamber, and said clean air chamber 100
7. The structure defined in claim 6 in which the separating chamber has an air inlet opening thereinto from the atmosphere, and provided with a device causing the incoming air to take a whirling motion within said separating chamber, said partition structure having a centrally located air port and an eccentrically located dust port, said air port connecting said separating chamber to said clean air chamber and said dust port connecting said separating chamber to said dust chamber, and said clean air chamber 105
8. The structure defined in claim 6 in which the separating chamber has an air inlet opening thereinto from the atmosphere, and provided with a device causing the incoming air to take a whirling motion within said separating chamber, said partition structure having a centrally located air port and an eccentrically located dust port, said air port connecting said separating chamber to said clean air chamber and said dust port connecting said separating chamber to said dust chamber, and said clean air chamber 110
9. The structure defined in claim 6 in which the separating chamber has an air inlet opening thereinto from the atmosphere, and provided with a device causing the incoming air to take a whirling motion within said separating chamber, said partition structure having a centrally located air port and an eccentrically located dust port, said air port connecting said separating chamber to said clean air chamber and said dust port connecting said separating chamber to said dust chamber, and said clean air chamber 115
10. The structure defined in claim 6 in which the separating chamber has an air inlet opening thereinto from the atmosphere, and provided with a device causing the incoming air to take a whirling motion within said separating chamber, said partition structure having a centrally located air port and an eccentrically located dust port, said air port connecting said separating chamber to said clean air chamber and said dust port connecting said separating chamber to said dust chamber, and said clean air chamber 120
11. The structure defined in claim 6 in which the separating chamber has an air inlet opening thereinto from the atmosphere, and provided with a device causing the incoming air to take a whirling motion within said separating chamber, said partition structure having a centrally located air port and an eccentrically located dust port, said air port connecting said separating chamber to said clean air chamber and said dust port connecting said separating chamber to said dust chamber, and said clean air chamber 125
12. The structure defined in claim 6 in which the separating chamber has an air inlet opening thereinto from the atmosphere, and provided with a device causing the incoming air to take a whirling motion within said separating chamber, said partition structure having a centrally located air port and an eccentrically located dust port, said air port connecting said separating chamber to said clean air chamber and said dust port connecting said separating chamber to said dust chamber, and said clean air chamber 130
